UNITED STATES PATENT OFFICE.

BENJAMIN JANOWSKY AND HYMAN G. ADLER, OF BROOKLYN, NEW YORK.

COLLAPSIBLE UMBRELLA.

Application filed October 20, 1922. Serial No. 595,823.

This invention relates to an improved umbrella adapted to be collapsed or folded into small compass; for convenience in storing, or to enable the owner to take it 5 advantageously with him on a journey or otherwise carry it about from place to place.

An object of this invention is to provide a collapsible umbrella comprising ribs which are capable of expanding and contracting, and remaining in expanded position when the umbrella is needed for use; the ribs being joined to a central rod or stem consisting of extensible sections that permit the rod to be readily shortened or 15 lengthened; the entire construction comprising parts that can be made from ordinary materials that are easily obtainable, and with the fewest possible number of different parts of varying dimensions; so that 20 the cost of manufacture is reduced to a minimum, while at the same time the umbrella can be of exceedingly practical design, easily operated, unlikely to get out of order and capable of giving long and continuous 25 service.

A further object of the invention is to provide a collapsible umbrella having a handle so united to the central stem that the handle also can be made to change its 30 position with respect to the stem when the umbrella is collapsed or folded; and thus contribute its own share to the limitation of the space which the umbrella, when entirely collapsed, will occupy.

Other objects and advantages of this 35 invention will be set forth in the following description, taken with the accompanying drawings; and the novel features of the invention will be defined in the appended 40 claims. The disclosure, however, is explanatory only and we reserve the right to make changes, particularly as to shape, size and arrangement of the parts, that do not depart from the spirit and scope of the invention, as indicated by the general meanings 45 of the terms in which the appended claims are expressed.

On the drawings:—

Figure 1 is a view partly diagrammatic 50 showing the central rod of the umbrella and the manner in which the ribs are attached to same; only one rib being included;

Figure 2 is a longitudinal section of the 55 rod to which the ribs are attached; the section being on the line 2—2 of Figure 3;

Figure 3 is an enlarged section on line 3—3 of Figure 2; presenting the parts in a slightly different position;

Figure 4 is an enlarged top view of a 60 collar which is attached to the upper end of the rod and unites the ribs thereto;

Figure 5 is a top view of a sliding collar or runner which loosely encircles the rod and enables the umbrella cover or top 65 to be distended or folded;

Figure 6 is a section on the line 6—6 of Figure 4;

Figure 7 shows the ribs and the cover in collapsed position, to be enclosed in a suit- 70 able container or casing;

Figure 8 shows in longitudinal section the lower end of the stem or rod of an umbrella according to our invention, with a handle shaped to receive some of the parts 75 of the umbrella when the latter is collapsed; and

Figure 9 is a cross section of the handle shown on Figure 8.

The same numerals identify the same 80 parts throughout.

In the particular description of what the drawings illustrate, we use the numeral 1 to indicate the central rod, which comprises sections that telescope one within the other 85 so that the rod can be shortened or drawn out to its full length, as desired. At one end the rod has a handle 2; and to the opposite extremity of the rod are pivotally secured the ribs 3 by which one can extend 90 or spread the cloth cover indicated at 4. Only one rib is shown in Figure 1; but obviously as many ribs as required may be secured to the rod 1, and radiate from same as an axis. Each of the ribs 3 is constructed 95 upon the principle of the lazy tongs so that only a small transverse movement of the component parts of the ribs will effect a great change in the length of the rib from the rod 1 outward. We shall first de- 100 scribe the character and construction of these ribs and the advantages afforded by them.

Each rib 3 comprises a number of struts 5, arranged in pairs. The struts of each 105 pair are joined near their middle points by pivots 6, and intersect each other; and the struts of the several pairs are united at their ends from the rod 1 outward to make a rib of the necessary length. The pivots which 110 unite the ends of the successive pairs of the struts together are indicated by the nu-

meral 7, and each rib terminates in an end strut 8, which is pivotally united to the extremity of the outermost strut 5 that has its outer end in uppermost position, when the umbrella is distended, as indicated in Figure 1. The outer end of the other strut of the same pair, which has its end in lowermost position, is pivotally connected to the middle of the end strut 8 by a short support 9. The two struts of each rib which are in innermost position; that is, closest to the rod 1, are indicated by the numeral 10, and these struts 10 are joined to the rod so that the rib can be operated as required. For such purposes, we secure to rod 1, near the end thereof opposite the handle 2, a fixed collar 11 having as many pairs of projecting lugs 12 as there are ribs 3; and the adjacent ends of the innermost struts 10 of each rib 3 which are in uppermost position are pivotally connected to the collar 11 by disposing the ends between the lugs 12; these lugs having notches 13; and by passing a wire through the inner ends of the struts 10 and causing this wire 14 to engage the inner ends of the notches 13; the ends of the wire of course being secured to each other. Thus, all the struts 10 and the collar 11 can be pivotally united to each other. Below the collar 10 is a sliding collar or runner 15 comprising lugs 12 having notches 13, similar to those on the collar 11; and the adjacent ends of the remaining inner struts 10, which will normally be located below the collar 11, can be united to the collar 15 by means of a wire 14 in the same way. This runner 15 has a downward extending neck 16 provided with a flange 17, that can be taken hold of by one's fingers and pushed up and down on the rod 1. When the runner 15 is moved away from the collar 11 the ribs 3 are shortened or contracted by being drawn inward towards the rod 1; and when the runner 15 is moved towards the collar 11 the ribs are expanded to distend or spread the cover 4. A spring 18 is attached to one of the struts 5 adjacent its midpoint and to an adjacent strut at a proper point. This spring 18 acts as indicated in Figure 1 to keep the ribs 3 expanded and to resist shortening or contracting. Hence, no catch or stop for the runner 15 is needed. When the cover is to be folded the runner 15 is simply pulled away from the collar 11. With the ribs or spreaders 3 collapsed, the springs 18 tend to make the umbrella open; and there is of course one spring for each rib 3.

The struts 5 are all of the same length except the end strut 8 and the support 9; consequently each rib consists of only three parts that are of different dimensions; because after the strut 8 and the support 9 are cut and shaped to the required length, all the other struts will be alike.

The rod 1 can be made of metal tubing which can be easily purchased in the trade and worked to give it the required shape. This rod consists of an upper section 19 having its upper end closed by the cap 20, and having an opposite or lower contracted end 21 providing an inside shoulder 22. The collar 11 and the runner 15 encircle this section; and the section 19 receives in the end 21 thereof the extremity of another section 23 having an expanded rim 24 located inside of the section 19. This rim 24, when the two sections are pulled out as far as the construction will permit, will engage inside shoulder 22; and at the same time when the rod is to be shortened the section 23 can be pushed into the section 19 until the expanded rim 24 about reaches the cap 20. The section 23 in its turn is provided with a contracted end 25 opposite the end having the expanded rim 24, giving an inside shoulder 26. The next section 27 telescopes within the section 23 and has an expanded rim 28, like the rim 24, to engage the shoulder 26 and limit the outward movement of the section 27. Near the end opposite the rim 28 the section 27 is provided with a circumferential groove 29.

We form a hole 30 in the end of the handle 2 and into this hole is driven a tubular insert or bushing 31; and the bushing and the handle are secured to each other by a pin 32. Outside of the handle the bushing 31 has slits 33 and an inside bead or rib 34 extending entirely around the circumference and across the slits 33. When the end of the section 27 having the groove 29 is forced into the bushing 31, the split end having the slits 33 will expand sufficiently to allow the section 27 to carry its groove 29 into position to receive the bead 34. The bushing 31 will therefore grip the end of the section 27 and hold the rod and handle together.

Hence, when one wishes to collapse the umbrella the ribs are first shortened by manipulating the runner 15 and then the section 23 can be telescoped into section 19 and the section 27 into the section 23; while to spread the cover 4 and expand the ribs and lengthen the rod 1, the reverse operation is performed.

For keeping the sections 19 and 23 in extended position, we secure to the inside of the sections 23 and 27, adjacent the rims 24 and 28 thereof curved springs 35 each of which has a cam-head 36. These cam-heads project through holes 37 in the upper ends of the sections 23 and 27 to engage openings 38 in the lower contracted ends of the sections 19 and 23. When the catches of the sections 23 and 27 engage the apertures 38 in the contracted ends of the sections 19 and 23, the sections of the rod 1 will of course be held in extended position; giving the rod its full length; while to shorten the

rod, the sections 19 and 23 must be released from the cam-heads 36, so as to permit the sections 23 and 27 to move upward and into the section 19. For this purpose we prefer to make one end of each cam-head 36 inclined; so that, for example, if the section 19, while it is engaged by the head 36 by virtue of this head entering the aperture 38 in the end 21 thereof, be turned in the direction of the arrow in Figure 3; the cam-head will be forced back out of the aperture 38; and the section 19 is released and can be turned enough to make the cam-head abut against the inside surface of the section 19. Then the section 23 can be pushed into the section 19; and so with the section 27.

As a result of this design, with the cam edges or faces of the catches in a plane transverse to the long axis of the rod 1, the umbrella rod can be shortened whenever the ribs 3 must be contracted. When the handle is shortened and the ribs contracted to fold the cover 4, the parts will all occupy the position shown in Figure 7, and be of such small compass that the umbrella can be inserted into a casing indicated at 39 adapted to be closed by a cap 40. When stored in this casing or container the handle 2 may be completely detached from the tubular section 27 and stowed between any two of the collapsed ribs 3. To detach the handle, the section 27 is pulled out of the insert 31; and this act permits the rod 1 to be further shortened by an amount corresponding to the length of the handle after the three sections are telescoped within one another. The casing 39 will be waterproof, to allow the umbrella to be temporarily stowed away without waiting to dry it, after using.

The umbrella is therefore very cheap to make, and as the material can easily be bought and easily worked, the invention can be produced at low cost. On account of the simplicity and other mechanical advantages of the design, mentioned above, the device is not likely to get out of order and is always easy to operate or collapse when it is to be carried about.

When expanded, the ribs will curve downward away from the top of the rod 1 as Figure 1 depicts. The pivots 6 are located further from the upper ends of the struts 5 which are adjacent the cover 4, than from the opposite or lower ends; and to this method of joining the equally long struts 5 in pairs, the curve or drop of the ribs 3 at their outer ends, is due.

Figures 8 and 9 show a special design of handle so united to one end of the rod or stem 1 that it can be moved with respect to the rod, and so shaped that it can receive the rib 3 when the umbrella, is collapsed.

The handle comprises a tubular body 41

having longitudinal slots 42 equal in number to the number of ribs 3, and these slots begin near one end of the body and open through the other, this other end being the upper end in Figure 8. Hence, the body will have the shape of a continuous ring at one end, from which ring extends, in a direction perpendicular to the plane of the ring, a number of upright fingers or prongs 43, between which the slots 42 are located. The lower end of the handle will be closed by a cap 44 which fits tightly into the body 41, and at the opposite end of the handle will be a cap 45 having circular slots 46 through which the prongs 43 can pass. Hence, the cap 45 can move towards and from the cap 44.

The cap 44 which fits into the body 41 is provided with an internal bushing or boss 47 which receives and has fixed therein one end of a rod 48. This rod passes through the handle 41 and beyond the opposite end thereof, and extends into the adjacent end of the tubular section 27. The cap 45 has a central bushing 49 and the lower end of the section 27 is reduced as at 50 and is inserted into the bushing 49 and soldered fast. Hence, if the handle be pushed in the direction of the section 27, the cap 44 moves towards the cap 45, the prongs 43 slide through the slots 46, and the rod 48 can be moved into the stem or rod 1; the cap 45 thus in effect movably or telescopically engaging the body 41 of the hollow handle, and serving as a guide head for the rod 1; but the handle cannot turn to an appreciable extent, because the section 27 is soldered to the cap 45 and the rod 48 is rigid with the cap 44 and body 41. At its upper end, inside the section 27, the rod 48 has a head or collar 51; and between the reduced end 50 and the body of the section 27 is a shoulder 52 which prevents separation of the rod 48 and section 27 by pulling out of the rod from this section. Near the head 51 the rod 48 has a recess 53, the rod 48 being shown as if broken away at its upper part in Figure 8 to reveal this recess; and registering with this recess in the reduced end 50 of the section 27 is a slot 54. The recess contains a catch 55 pivoted on a pin 56 and a spring 57 having one end in a notch at the upper extremity of the recess 53 and the other extremity engaging a notch in the catch 55 normally moves the free end of this catch into the slot 54, and makes the end of the catch abut the upper end of the slot 54 in the section 27; so as to hold the section 23 and handle 41 against telescoping movement when the umbrella is distended.

When the umbrella is to be collapsed the ribs 3 are contracted, the catches 36 are released and the section 23 is moved up into the section 19 and the section 27 into the section 23. The reduced end 25 of the sec-

tion 23 will first engage the beveled end of the catch 55 and move it inward so as to cause the squared or abrupt end of this catch to disengage the upper end of the slot 54, 5 and then the movement of the section 27 along the rod 48 as the cap 45 moves into the body 41 will force the catch 55 further into the recess 53 against the action of the spring 57; thereby allowing movement of 10 the rod 48 into the section 27, and of the cap 45 down as far as the cap 44. The travel of the cap 45 into the handle exposes the open ends of the slots 42, and as the stem 1 is shortened the contracted ribs 3 enter 15 these slots and are thus housed in the handle. The entire structure can then be enclosed in the casing 39. When the ribs enter the slots 42 the collar 15 may also pass into the handle 41 because it is made smaller than 20 the inside diameter of the handle. To expand the umbrella again the handle is simply pulled to extend the sections 19, 23 and 27, and draw the head 51 against the shoulder 52 of the section 27 and the slot 54 into 25 position to let the catch 55 move out into it.

Having described our invention, what we believe to be new and desire to secure and protect by Letters Patent of the United States is:—

A collapsible umbrella having a cover and 35 expandible ribs to distend the cover, each of said ribs comprising struts of equal length and arranged in pairs, the struts of the several pairs being pivotally united together at their ends, the struts each having one end 35 adjacent the cover and the opposite end remote therefrom, the struts of each pair being pivotally united at points which are relatively farther from the ends of the struts 40 adjacent the cover than from the opposite ends, the rib when expanded curving from one end to the other, and a spring for each rib attached at its ends to the struts in position to exert a force tending to expand the rib. 45

In witness whereof, we have signed our names to this specification this 25th day of September, 1922.

BENJAMIN JANOWSKY.
HYMAN G. ADLER.
